(73) Assignee: **Empire Level Mfg. Co.**, Mukwonago, WI (US)

(57) **CLAIM**

The ornamental design for a side brace for central-vial region of a box level, as shown and described.

DESCRIPTION

FIG. 1 is a perspective view of the side brace for central-vial region of a box level, a central portion of the brace and a shown fragment of the box level are shown in phantom lines; FIG. 2 is a front elevation of the side brace for central-vial region of a box level of FIG. 1;

FIG. 3 is a top view of the side brace for central-vial region of a box level of FIG. 1; and,

FIG. 4 is a perspective view of the side brace for central-vial region of a box level of FIG. 1, the entire box level is shown in phantom lines.

The word DeWALT® as seen molded in FIGS. 1, and 4 is not part of the design.

The broken lines are provided for illustrative purposes only and form no part of the claimed design.
